A. H. JEWELL

INSULATING ATTACHMENT FOR OIL STOVE CHIMNEYS

Filed March 29, 1923

Inventor *Albert H. Jewell*
By *Dodson & Rose, Atty.*

UNITED STATES PATENT OFFICE.

ALBERT H. JEWELL, OF LAWRENCE, KANSAS, ASSIGNOR TO THE PERFECTED CHIMNEY COMPANY, OF LAWRENCE, KANSAS, A CORPORATION OF KANSAS.

INSULATING ATTACHMENT FOR OIL-STOVE CHIMNEYS.

Application filed March 29, 1923. Serial No. 628,476.

To all whom it may concern:

Be it known that I, ALBERT H. JEWELL, a citizen of the United States, residing at Lawrence, in the county of Douglas and State of Kansas, have invented a certain new and useful Improvement in Insulating Attachments for Oil-Stove Chimneys, of which the following is a specification.

My invention relates to the art of oil stoves, burners and the like, in which a heat conveying chimney is used, and has for its object to provide an attachment for oil stove chimneys, in general use, which will utilize a larger proportion of the heat units and also intensify the heat which is produced.

In some chimneys for oil stoves which are now in general use there is no insulation whatsoever employed and the heat rays impinging upon the usual metal wall of the chimney are, in a large measure, absorbed and portions thereof pass through the chimney wall and are lost, to all practical purposes, for their designed function.

My purpose is to provide a lining for such chimneys as will be adapted to retain the heat units within the chimney by which they will be directed upwardly to the utensil on the stove. A further object is to have this lining reflect the heat rays impinging thereon back into the chimney thereby intensifying the heat which is conveyed upwardly for its practical purpose.

A further object is to provide such a lining in a construction that can be easily and quickly attached to any of the standard make oil stove chimneys by any person whether skilled in the art or not.

I accomplish my objects by means of the details of construction hereinafter set forth, pointed out in my claims and illustrated in the accompanying drawings, in which Fig. 1 shows a plan view of an oil stove chimney, my device being in place therein.

Fig. 2 shows a sectional view taken on the line A—A in Fig. 1;

Fig. 3 shows a sectional view taken on the line B—B in Fig. 1; and

Fig. 4 shows a detail view of a portion of the lining being held in place by the shoulder above the door in a chimney.

Fig. 5 shows a detail view of one of the blocks.

Referring to the accompanying drawings the reference numeral 10 is used to indicate

an oil stove chimney of the ordinary type, 55 with a door opening 11 formed therein, said door opening usually having the shoulder 12 formed at the top thereof. Obviously the top and bottom of the chimney are open as shown. 60

My attachment consists of a plurality of mating blocks of material, 13 and 14 formed to resist the heat rays and reflect them back into the chimney, designed to form, in their combination, a lining for the chimney. 65 These blocks are, obviously, curved to fit the inner surface of the chimney and, preferably, the chimney is laid in a horizontal position with the door opening at the top. The blocks 13 are designed to extend the 70 complete inner length of the chimney and mate as shown, and the number of such blocks used are designed to fill the complete inner surface of the chimney except for the space above the door. Key stone blocks 14 75 are then inserted through the door their beveled longitudinal edges 15 mating with the beveled longitudinal edges 16 of their adjacent blocks (on each side thereof) and the block 14 is then forced upwardly to the 80 top of the chimney. Other key stone blocks are inserted through the door in the same manner their upper edge surfaces engaging the lower edge surfaces of the blocks 14 85 which have theretofore been inserted, until the space above the door has been completely filled, the lower supporting block 14 resting on the shoulder 17 formed in the chimney above the door. By this method of assembly it is obvious a complete inner lining for 90 the chimney, made up of a plurality of mating blocks, has been provided. 95

Minor changes in details of construction of my device may be employed without in any manner affecting my invention or its 95 function and I do not wish to be limited in the scope of my invention except as set out in the appended claims.

Having thus described my invention what I claim and desire to secure by Letters Patent of the United States, is:

1. An inner wall lining for oil stove chimneys of cylindrical formation with doors formed in the wall thereof comprising a plurality of mating longitudinal blocks extending from the base to the top of the chimney, said blocks covering the inner wall of the chimney except for the space above

the door, key stone blocks filling the space above the door and locking all blocks in relative position to form a complete lining.

2. An inner wall lining for oil stove chimneys of cylindrical formation with doors formed in the wall thereof comprising a plurality of mating longitudinal blocks extending from the base to the top of the chimney, said blocks covering the inner wall of the chimney except for the space above the door; key stone blocks filling the space above the door and locking all blocks in relative position to form a complete lining and means to support the key stone blocks.

ALBERT H. JEWELL.
